(57) **CLAIM**

The ornamental design for a quadruple bubble solar pool cover, as shown and described.

DESCRIPTION

FIG. 1 is a front, left and top perspective view of a quadruple bubble solar pool cover showing my design.

FIG. 2 is a rear, right and bottom perspective view of a quadruple bubble solar pool cover showing my design.

FIG. 3 is a front elevation view thereof.

FIG. 4 is a rear elevation view thereof.

FIG. 5 is a left-side elevation view thereof.

FIG. 6 is a right-side elevation view thereof.

FIG. 7 is a top plan view thereof.

FIG. 8 is a bottom plan view thereof.

FIG. 9 is an enlarged view of a portion indicated in FIG. 1; and,

FIG. 10 is an enlarged view of a portion indicated in FIG. 2. The broken lines in the drawings illustrate the boundaries of FIGS. 9 and 10 and form no part of the claimed design.
